UNITED STATES PATENT OFFICE.

DAVID ELMER ROBERTS, OF RACINE, WISCONSIN.

LIGHTING-FIXTURE.

1,302,712.

Specification of Letters Patent.

Patented May 6, 1919.

Application filed September 12, 1918. Serial No. 253,787.

To all whom it may concern:

Be it known that I, DAVID ELMER ROBERTS, a citizen of the United States, residing at Racine, in the county of Racine and State 5 of Wisconsin, have invented a certain new and useful Improvement in Lighting-Fixtures, of which the following is a specification.

My invention relates to that class of devices which are designed to utilize stock parts, and to produce a simple and inexpensive semi-indirect unit which will be efficient.

My means of accomplishing the foregoing 15 objects may be more readily understood by having reference to the accompanying drawing, which is hereunto annexed and is a part of this specification, in which:

Figure 1 is a side elevation of a lighting fixture embodying my improvement.

Figs. 2 and 3 are enlarged fragmentary detail views of the supporting means.

Similar reference numerals refer to similar parts throughout the entire description.

As shown in the drawing, the lighting fixture comprises a canopy or suitable ceiling support 4, from which depends a chain 5, to a holder 6. This holder is provided with a collar 7, provided with set screws 30 8, which are adapted to engage the neck 9, of a flat opal shade, or reflector 10. The electric light bulb 11, is mounted in a socket 12, secured in the holder 6, and the filament of the lamp bulb 11, extends into a 35 shield or bowl 13. This bowl is supported by my improved holder 14, which comprises a ring, which is formed of a plurality of sections, 15, 16 and 17. As illustrated, it is provided with three sections, though it

40 is obvious that it can be made of any desired number. The adjacent ends 18 and 19, of the sections are entwined together, and terminate in hooks 20, which are adapted to engage the periphery of the flat opal 45 reflector 10.

Inasmuch as the material of which the bowl supporting ring is formed is of resilient material, there is sufficient spring in the ends 18, and 19, so as to clamp the periphery of the shade firmly. They being made of smaller diameter than the diameter of the shade necessitates their being sprung outwardly to enable them to engage the edge of the shade, and the resiliency of the material causes them to clamp it firmly. 50

It is apparent from the foregoing description and an inspection of the drawing, that my device provides a shadowless fixture, in which the engagement of the bowl with the reflector is entirely automatic, and does not 60 require any adjustment. Consequently the fixture can be assembled without the use of a skilled electrician or lighting fixture mechanic.

Having described my invention what I 65 regard as new and desire to secure by Letters Patent of the United States, is:

1. In a lighting fixture, the combination of a holder with a flat opal reflector, a bowl below said reflector, bowl supporting means 70 comprising a ring formed of a plurality of sections, the ends of said sections being bent upwardly and entwined together, the ends terminating in hooks which engage the periphery of the reflector. 75

2. In a lighting fixture, the combination of a holder with a flat opal reflector, a bowl below said reflector, bowl supporting means comprising a ring formed of a plurality of sections, the ends of said sections being bent 80 upwardly and entwined together, the ends terminating in hooks which engage the periphery of the reflector, said ring and sections being formed of resilient material. 85

In testimony whereof, I have signed the foregoing specification.

DAVID ELMER ROBERTS.
